UNITED STATES PATENT OFFICE

170,428

CALKING GUN

Wilber P. Peterson, Kansas City, Mo.

Application September 25, 1952, Serial No. 21,579

Term of patent 14 years

(Cl. D46—1)

To all whom it may concern:

Be it known that I, Wilber P. Peterson, a citizen of the United States, residing at Kansas City, in the county of Jackson and State of Missouri, have invented a new, original, and ornamental Design for a Calking Gun, of which the following is a specification, reference being had to the accompanying drawings, forming part hereof.

In the drawings:

Fig. 1 is a perspective view of a calking gun showing my new design.

Fig. 2 is a side elevational view thereof.

Fig. 3 is a front elevational view thereof.

Fig. 4 is a top plan view thereof.

I claim:

The ornamental design for a calking gun, as shown.

WILBER P. PETERSON.
